UNITED STATES PATENT OFFICE.

WILLIAM CRISTIAN MEYER, OF BEVERLY, MASSACHUSETTS. ASSIGNOR TO UNITED SHOE MACHINERY CORPORATION, OF PATERSON, NEW JERSEY, A CORPORATION OF NEW JERSEY.

SHOE-SEWING MACHINE.

1,411,797.

Specification of Letters Patent. Patented Apr. 4, 1922.

Application filed April 7, 1920. Serial No. 372,030.

To all whom it may concern:

Be it known that I, WILLIAM C. MEYER, a citizen of the United States, residing at Beverly, in the county of Essex and State 5 of Massachusetts, have invented certain new and useful Improvements in Shoe-Sewing Machines; and I do hereby declare the following to be a full, clear, and exact description of the invention, such as will enable 10 others skilled in the art to which it appertains to make and use the same.

This invention relates to machines for sewing a welt and an upper to the insole of a welted shoe and, more particularly, to devices for holding the end of the welt in position at the beginning of a sewing operation.

The primary object of the invention is to improve and simplify the construction and 20 mode of operation of the devices in machines of this class, for holding the end of the welt in position to be attached to the upper and insole during the first part of a seam formation.

25 With this object in view the invention consists in certain novel and improved constructions, arrangements and combinations of parts hereinafter described and particularly pointed out in the claims, the advantages of which will be readily understood and appreciated by those skilled in the art.

The invention is designed particularly as an improvement on the machine illustrated and described in applicant's pending application, Serial No. 95,893, filed May 6, 1916, renewed June 17, 1920, Serial No. 389,774. The machine covered by this application is provided with devices for gripping and severing the welt between the shoe and the machine upon the completion of a seam and with a welt holder which acts in cooperative relation with these devices. Certain features of the invention, however, are not limited to use in combination with devices for gripping and severing the welt, but may be embodied in machines in which the welt is severed by hand.

50 The invention will be readily understood from the accompanying drawings illustrating a machine embodying the invention in its preferred form, and the following detailed description of the constructions therein shown.

In the drawings Figure 1 is a view in side 55 elevation of a shoe sewing machine embody-

ing the invention; Fig. 2 is a view in horizontal section illustrating particularly the devices for handling the welt; Fig. 3 is a view in side elevation, partly broken away and partly in section, looking from the right 60 and illustrating particularly the welt severing and gripping mechanism and the welt holder mechanism; Fig. 4 is a view in vertical section illustrating the welt severing and gripping mechanism and the welt holder 65 mechanism; Fig. 5 is a detail view in side elevation looking from the left and illustrating the welt holder mechanism, and Fig. 6 is a detail plan view of one of the parts shown in Figs. 2 and 4.

70 The machine illustrated in the drawings has the same general construction, arrangement and mode of operation of parts as the machine illustrated and described in applicant's pending application referred to above. 75 The machine comprises an oscillatory curved hook needle 2 and devices cooperating therewith to form a chain stitch seam, an awl or feed point 4, a channel guide 6, and a welt guide 8. All of these parts and their operating mechanisms have substantially the same construction, arrangement, and mode of operation as the corresponding parts of the machine covered by applicant's pending application and need not be further described 80 85 herein.

86 The devices for severing and holding the welt at the completion of the sewing operation, are substantially the same as in the machine of applicant's pending application 90 and comprise welt gripping jaws 10 and 12, and a welt severing knife 14 which are held in retracted position during the sewing of a shoe and are advanced to sever and hold the welt after the sewing operation has been 95 completed and the machine brought to rest. The welt gripping jaws are respectively formed on levers 16 and 18 pivoted on the forward end of a gripper slide 20 and acted upon by a spring 22 which normally holds 100 the levers in position with the gripping jaws open. The knife 14 is secured to the forward end of a slide 24 mounted to slide in guides in the gripper slide 20.

105 The gripper slide is advanced with the knife slide during the first part of the advancing movement of the knife slide through the engagement of rolls 26 mounted on the knife slide with the rear end of the lever 16, the lever then being held from pivotal move- 110

ment by the engagement of a lateral projection on the rear end of the lever with the plate 30. The forward movement of the gripper slide is limited by the engagement 5 of a projection 27 on the slide with the rear end of the guide-way through which the slide moves. When the gripper slide reaches the limit of its forward movement the lateral projection on the lever 16 is in position to 10 engage in a recess in the plate 30, allowing the rear end of the lever to swing upwardly out of the path of the rolls 26, and the knife slide continues its forward movement independently of the gripper slide, the levers 15 16 and 18 being actuated by the rolls 26 to close the welt gripping jaws during this movement of the knife slide. During the first part of the retracting movement of the knife slide the gripper slide is held stationary 20 through the engagement of the lateral projection on the lever 16 in the recess in the plate 30. At a certain point in the retracting movement of the knife slide the rolls 26 are disengaged from the lever 16 25 allowing the lever to be actuated by the spring 22 to disengage the lateral projection thereon from the recess in the plate 30, and the gripper slide is then retracted with the knife slide by the engagement of a boss 30 31 on the knife slide with the rear end of a slot 28 in the gripper slide.

The mechanism for advancing and retracting the knife slide comprises a pivoted gear segment 32 meshing with rack teeth 35 formed on the knife slide, a heavy coiled spring 34 for swinging the gear segment in a direction to retract the knife slide, a bell crank lever 36 connected with the gear segment by means of a link 38, an intermittently rotating eccentric 40 mounted on the main shaft 42 of the machine and connected with the bell crank 36 by an eccentric strap 44 for actuating the gear segment 32 to advance the knife slide. The knife slide is held in advanced position by the engagement 40 with the rear end of the slide of a pivoted latch lever 46 which is actuated to release the knife slide through the engagement of a roll 48 carried by said lever with 45 a cam formed on the periphery of a cam disk mounted on the main shaft 42.

The eccentric 40 is normally held stationary and is arranged to be driven from the main shaft 42 through a Horton clutch (not 55 shown) which is controlled by means of latches 50 and 52 arranged to act on a clutch controlling member 54. The latch 50 which holds the clutch controlling member stationary and the clutch out of action during the 60 normal operation of the machine is connected by means of a shaft 56, an arm 58 and a rod 60 with a lever 62 arranged to be actuated by the forward pull imparted to the welt in removing a shoe from the machine. The actuation of this lever through

the connections described throws out the latch 50 and causes the clutch to be thrown into operation to advance the cutter slide 24, the clutch controlling member being caught by the latch 52 to throw the clutch 70 out of operation. The latch 52 is actuated to release the clutch controlling member upon starting the machine, and to this end is connected through a hollow shaft 64 with an arm 66 carrying a cam roll 67 arranged to engage a peripheral cam formed on a cam disk mounted on the main shaft 42. Upon its release by the latch 52 the clutch controlling member is caught by the latch 80 50. The mechanism for advancing and retracting the welt cutter slide and the welt gripper slide, briefly described above, has the same construction, arrangement and mode of operation as the corresponding mechanism of the machine covered by applicant's above application, and reference may be had to said application for a full and complete description of the same.

The present machine is preferably provided with mechanism, like the machine of applicant's pending application which is under the control of the operator and, which when thrown into operation acts to arrest the forward rotation of the main shaft, then to impart a reverse rotation to the shaft, and finally to bring the shaft to rest at a predetermined point in its rotary movement. The reverse rotation imparted to the shaft reverses the cycle of operations of the stitch forming mechanism to cast off the thread 100 from the needle, and the shaft is finally brought to rest with the needle in retracted position to permit the ready removal of the shoe. As the operator disengages the shoe from the machine, a movement is imparted to the shoe to draw the welt forward through the welt guide, thereby actuating the lever 62 to throw the mechanism for advancing the welt cutter and gripper slide into operation. The welt gripping jaws are thus advanced into positions on opposite sides of the welt in advance of the needle, are relatively actuated to grip the welt, and the welt cutting knife then acts to sever the welt. The welt gripping and severing devices remain in the positions which they thus assume until a new seam is started. Upon the starting of a seam upon the succeeding shoe, the latch lever 46 is actuated to release the cutter slide, the welt gripping jaws are relatively actuated to release the welt and the welt cutter and gripper slides are retracted to their normal positions. To hold the free end of the welt in position to be attached to the shoe after it 110 is released by the welt gripping devices, the present machine like the machine of applicant's pending application is provided with a supplementary welt holder which is normally held in retracted position out of 125 130

operation and is thrown into operation upon starting the machine. As the welt cutter and gripper slides are retracted, the welt holder is moved forward into engagement 5 with the welt between the extreme end thereof and the needle is moved laterally in the direction of feed during the initial feeding movement of the shoe, and is then retracted out of operating position. The mechanism 10 for controlling and operating this welt holder is of simplified and improved construction. The welt holder indicated at 68, consists of a finger mounted on a carrier 70 and is arranged to engage the outer 15 side of the welt and press the same into contact with the shoe. The carrier 70 is pivoted by means of a pivot stud 72 on the forward end of a slide 74. The welt holder is advanced and retracted by the movements 20 of the slide 74, and is carried in the direction of the line of feed by swinging the carrier 70 about the pivot stud 72. The slide 74 is acted upon by a coiled spring 76 connected with a forwardly extending 25 arm on a bracket 77 secured to the rear end of the slide which tends to advance the slide. The slide, however, is normally held in retracted position by means of a latch 78 pivoted at 30 80 on the frame, the rear end of which is arranged to engage a projection formed on the bracket 77. The latch is 35 actuated upon by a spring 84 which tends to depress the rear end thereof into acting position. The latch 78 is actuated to release the slide 40 74 as the gripper slide 20 is retracted. To this end a dog 86 is pivoted on a stud 88 carried by the gripper slide and is arranged to engage a projection 90 formed on the forward end of the latch. The dog 86 is acted 45 upon by a light coiled spring 92 which tends to depress the acting end thereof, and the movement of the dog under the action of the spring is limited by the engagement of a projection on the dog with a stop 94 on the gripper slide. The projection 90 is formed with oppositely inclined forward and rear faces, as clearly shown in Fig. 3, arranged to be engaged by the acting end of the dog 86. 50 During the normal operation of the machine, the gripper slide and welt holder slide both then being in retracted position, the acting end of the dog 86 is located behind the projection 90. During the advancing 55 movement of the gripper slide the dog is lifted by its engagement with the rear inclined face of the projection 90, the dog passing idly by the projection. During the retracting movement of the gripper slide the dog 60 engages the forward inclined face of the projection 90, and the forward end of the latch 78 is depressed, thereby releasing the welt holder slide 74 and allowing the same to be advanced by the coiled spring 76. 65 After the initial feed of the shoe has taken place, the slide 74 is retracted to its normal position by means of a cam lever 96 pivoted at 98, the lower end of which is arranged to engage an abutment 100 formed on the forwardly extending arm of the bracket 77, 70 and the upper end of which carries a cam roll 102 arranged to engage in a cam groove in a cam disk mounted on the main shaft 42. When the slide reaches its retracted 75 position the latch 78 engages in front of the projection on the bracket 77 and holds the parts in position. The mechanism for swinging the carrier 70 to move the welt holder in the direction of feed comprises a slide 104, one end of which 80 is pivotally connected at 106 with a continuously oscillating lever 108, and the other end of which engages in a guide-way in the frame of the machine, as clearly shown in Figs. 2 and 4. The slide 104 carries a catch 85 110, pivoted on a stud 109 and having a depending projection 111 arranged to engage an upstanding projection 112 formed on a rearwardly extending arm on the carrier 70. The catch 110 is acted upon by a coiled 90 spring 114 which normally maintains the same in the position shown in Figs. 2 and 4, the movement of the catch under the action of the spring being limited by the engagement of a stop 116 on the catch with the 95 slide 104. The lever 108 is the lever by which the feed slide is actuated. When the machine is stopped with the needle in its limiting retracted position, the parts of the machine occupy the positions which they 100 assume at a point in a cycle of operations when the feeding devices have executed only a part of their advance movement. Upon starting the machine these devices complete their advance movement at once, the 105 lower arm of the feeding lever 108 then swinging to the left. As the slide 74 is advanced to carry the welt holder into engagement with the shoe the projection 112 on the welt holder carrier engages the rear 110 side of the projection 111 on the catch 110 and swings the catch forwardly. As the lower arm of the feeding lever swings to the left, however, the projection 111 is carried 115 to the left beyond the projection 112 and the catch 110 is then swung rearwardly into acting position. Then as the feeding lever 108 is swung in the opposite direction the carrier 70 is swung in a direction to carry the welt holder in the direction of feed by 120 the engagement of the projection 111 with the projection 112. As the slide 74 is retracted the projection 112 is disengaged from the projection 111 by the rearward movement of the carrier 70. 125

Having explained the nature and object of the invention, and having specifically described a machine embodying the invention in its preferred form, what is claimed is:

1. A welt shoe sewing machine having, in 130

combination, stitch forming mechanism including a curved hook needle, welt cutting and gripping devices, means for advancing and retracting said devices, a welt holder, a spring for advancing the welt holder, a latch for holding the welt holder in retracted position, means operated by the welt cutting and gripping devices during their retracting movement for releasing the latch, and means for retracting the welt holder.

2. A welt shoe sewing machine having, in combination, stitch forming devices including a curved hook needle, welt cutter and welt gripper slides, means for advancing and retracting said slides, a welt holder, a spring for advancing the welt holder, a latch for holding the welt holder in retracted position, a pivoted dog carried by one of said slides for engagement with the latch, arranged to pass idly by the latch during the advancing movement of the slide and to throw out the latch during the retracting movement of the slide, and means for retracting the welt holder.

3. A welt shoe sewing machine, having in combination, stitch forming devices including a curved hook needle, welt cutting and gripping devices, a welt holder, a slide upon which the welt holder is mounted, a spring for advancing the slide, a pivoted latch for engagement with an abutment on the slide for holding the slide in retracted position, means operative by the welt cutting and gripping devices during their retracting movement for releasing the latch, and a cam lever for engagement with an abutment carried by the slide for retracting the slide.

4. A welt shoe sewing machine having in combination, stitch forming devices including a curved hook needle, welt cutter and welt gripper slides, a welt holder, a welt holder slide, a spring for advancing the welt holder slide, a pivoted latch for engagement with an abutment on the welt holder slide for holding said slide in retracted position, a pivoted dog carried by one of said first slides for engagement with

the latch arranged to pass idly by the latch during the advancing movement of said slide and to throw out the latch during the retracting movement of the slide, and a cam lever arranged to engage an abutment carried by the welt holder slide for retracting the welt holder slide.

5. A welt shoe sewing machine, having in combination, stitch forming devices including a curved hook needle, a forwardly and rearwardly movable welt holder slide, a welt holder, a carrier therefor pivoted on the slide, a second slide mounted for movement in the direction of feed, means for constantly reciprocating the slide, and a pivoted catch carried by the latter slide for engagement with said carrier to swing same and thereby move the welt holder in the direction of feed.

6. A welt shoe sewing machine having in combination, stitch forming devices including a curved hook needle, a welt holder, a carrier therefor mounted for forward and rearward movement and also for movement to carry the welt holder in the direction of feed, a member mounted for reciprocatory movement in the direction of feed, means for constantly reciprocating said member and a catch carried by said member for engagement with the carrier to actuate the same to move the welt holder in the direction of feed arranged to be engaged with and disengaged from the carrier respectively by the forward and rearward movements of the carrier.

7. A welt shoe sewing machine having in combination, stitch forming devices including a curved hook needle, a welt holder, a movable carrier therefor, means for advancing and retracting the carrier and means for moving the carrier to carry the welt holder in the direction of feed comprising a slide, means for constantly reciprocating the slide and a pivoted catch for connecting the welt holder with the slide.

WILLIAM CRISTIAN MEYER.
